FIG. 4.

UNITED STATES PATENT OFFICE

2,595,414

ELECTRIC SWITCH CONTROL STATION

Carl A. Schaefer, Milwaukee, Wis., assignor to
 Square D Company, Detroit, Mich., a corpora-
 tion of Michigan

Application September 22, 1949, Serial No. 117,188

12 Claims. (Cl. 200—5).

1

This invention relates to electrical control stations. More specifically, this invention relates to control stations for electrical systems comprising a plurality of switching mechanisms actuated by an operating lever acting through camming means which determine the switch operation.

In many industrial applications, and particularly in textile manufacturing, it is desirable to use magnetic starters with a control mechanism which will be both sturdy and compact, and which will, when placed in operative position in an electric motor circuit, provide for starting and stopping of the motor, "inching" or "doffing" operation with only a small movement of an operating handle, and which will provide connections for both low voltage and overload control of the electric motor, with the requirement that the operating handle be moved to "off" position following a condition of overload or low voltage before the motor can be reenergized. It is therefore an object of the present invention to provide a control mechanism which provides all of the above desired features and which further provides for great flexibility of operation, by permitting reverse operation of the device by a simple switching of terminal connections.

Another object of the invention is the provision of an electrical control station providing for the sequential operation of a pair of switches by a pair of operating levers having cam surfaces acted upon by the operator for the station.

Another object of the invention is the provision of an electrical control station in accordance with the preceding object in which one of the levers is provided with cam surface elements at opposite sides of the cam surface element on the other lever so as to provide for the desired alternate operation of the switches as the operating lever is moved.

Further objects and features of the invention will be readily apparent to those skilled in the art from the specification and appended drawings illustrating certain preferred embodiments in which:

Figure 1 is a front elevational view of the device of the present invention in which a portion of the cover is broken away to show the internal structure.

Figure 2 is a sectional view along the line II—II of Figure 1.

Figure 3 is a detail view along the line III—III of Figure 1.

Figure 4 is a sectional view similar to Figure 3 with the parts in another operating position.

Figure 5 is a sectional view similar to Figure 3 with the parts in a third operating position.

Figure 6 is a detail view of the double stepped camming member employed in the device.

Figure 7 is a detail view of the single stepped camming member employed in the device.

Figure 8 is a detail view of the switching mech-

2

anism employed in the present invention as viewed along the line VIII—VIII of Figure 1.

Figure 9 is a schematic view of the circuit employed in cooperation with the device of the present invention.

The device of the present invention comprises a metal boxlike structure 1 having mounting holes 2 and provided with a metal cover 3 secured to the box 1 by suitable securing screws 4. Extending through an aperture in a raised portion 5 on the bottom of the box 1 and through a suitable recess in the right side of the box 1, as viewed in Figure 1, is an operating shaft 6, on the exterior end of which a slotted operating handle 7 is clamped by means of the screw member 8. Disposed between the operating handle 7 and the outer wall of the box 1, and also mounted upon the operating shaft 6, is a rotational limiting disc 9 which cooperates with a stud 11 which projects from the outer wall of the box 1 to permit rotation of the operating handle 7 through an arc of approximately 100 degrees, the operational arc, as shown, having as limits the vertical position shown in Figure 1 and a position approximately 100 degrees away from that vertical position in a forward direction, perpendicular to the plane of Figure 1.

Upon the interior end of the operating shaft 6 there is secured a circular operating disc 12 which is fastened to the operating shaft 6 by a screw 13 preventing any relative movement between the shaft 6 and the disc 12. An operating stud 14 projects from the disc 12, the stud 14 serving to rotatably mount a roller member 15 of a suitable, hard material, the roller member being loosely mounted upon the stud 14 and capable of rotational movement thereon.

The roller member 15 abuts against two camming members 16 and 17, the member 16 being shown in Figure 6 and having two camming steps 18 and 19. In Figure 7, the member 17 is shown; it has but one camming step 21 which, however, is about twice as large as either step 18 or 19. A pair of posts 22 and 23 are provided projecting from the bottom of the box 1 with the member 16 having a stud 24 rotatably mounted within a suitable aperture in the post 22, while the member 17 has a similar stud 25 rotatably mounted within a suitable aperture in the post 23. The two camming members 16 and 17 are therefore mounted in juxtaposed position, the member 16 being closest to the observer in the views shown in Figures 2—5.

A projection 26 extends from, and perpendicular to the plane of, the cam member 16 and carries a screw 27 having operating head 29, the screw 27 and projection 26 being biased away from the bottom of the base 1 by a spring 28. For the purpose of explaining the operation of the device, this end of the member 16 will be termed the operative end thereof.

In a like manner, the cam member 17 carries a perpendicular projection 31 which extends therefrom, and carries a screw 32 with operating head 34 and with the combination biased away from the bottom of the base 1 by a spring 33. Employing terminology analogous to that used in describing member 16, this end of the member 17 will be termed the operative end.

Projecting from the bottom of the box 1 are four posts 35, two of which, as may be seen in Figure 8, support a switching device 36, the other pair serving to support a switching device 37, mounting screws 38 being used to maintain the switching devices in position upon their respective posts. The switching devices 36 and 37 are identical in construction, the device 36, as employed in the specific embodiment herein described, being illustrated in Figure 8. The device 36 comprises an exterior boxlike member, which is broken away in Figure 8 to facilitate explanation, upon which are disposed a pair of exterior terminals 62 and 63 (indicated by the letter "A" in Figure 9) which are electrically connected to a pair of stationary contacts 42 and 43. These contacts cooperate with movable contacts 44 and 45 respectively, the latter pair of contacts being mounted on a bridging conducting member 46 which is normally maintained in the position shown in Figure 8 by a spring 47 which biases an operating button 48 outwardly. Leaf springs 49 are provided to effect snap action of the movable contacts, upon operation of the button 48, from the position shown in Figure 8 to that position in which they contact a second pair of stationary contacts 51, 52 electrically connected to a pair of external terminals also mounted upon the boxlike enclosure and shown diagrammatically as "B" in Figure 9, and numbered 69 and 71.

The switching device 37 is shown in Figure 9 to also have two pair of terminals C and D, the terminals C, shown as 66 and 68, being electrically connected to the pair of stationary contacts which are bridged by the movable contacts when the operating button of device 37 is in its extended, outward position. Conversely, the D terminals 72 and 73 are electrically connected to the pair of stationary contacts which are bridged by the movable contacts when the operating button is depressed.

Both of the switching devices 36 and 37 employed in this device are of the type in which snap action occurs at one position of the operating button as the button is moved "in," and at another, different position as the operating button moves "out." For example, in one form of switch, snap action occurs during the "inward" movement at a position at which the operating button is depressed about 0.05 inch from its normal extended position; while snap action occurs during the "outward" movement when the operating button is only about 0.015 inch from its normal position. This particular switch was the subject of an application of Hermon L. Van-Valkenburg for Electric Switch, Serial No. 866,289, filed May 1, 1946, this application having been abandoned. It should be noted, however, that the device of the present invention is in no way limited to the use of this particular switch, which of itself forms no part of the present invention, as devices in which the snap action occurs to operate the switch at one position as the actuator is moved in, and at another position as the actuator is moved out, are well known. For example, one such switch of this general type is shown and described in Patent No. 2,476,056,

issued July 12, 1949, the patentee being Wilbert A. Martin (See column 3, lines 42-56).

In Figure 9 the device of the present invention is shown in operative position in an electric circuit which comprises an electric motor 53 which is connected to supply lines 54, 55 and 56 through conventional circuit protecting equipment and normally open contacts 57 after a coil 58, controlling the closure of the contacts 57, has been energized through the device of the present invention, as subsequently described. Normally open holding contact 74 is provided for the motor contactor and is also controlled by the energizing coil 58. A conductor 59 interconnects a holding contact 74 and terminal 62. A conductor 61 interconnects coil 58 and terminal 63. A conductor 64 interconnects line terminal 56 with terminal 66. Conductor 67 interconnects terminals 62 and 68.

The device of the present invention operates in the following manner:

With the circuit connections as shown in Figure 9, the vertical position of the handle corresponds to the "off" position and the internal members of the device of the present invention assume the position shown in Figure 3, with the roller 15 abutting against the camming members 16 and 17 as shown. In this position, the operative end of member 16 is depressed against the bias of spring 28 by the roller 15 while the surface of the cam member 17 is such that the operative end of member 17 is in raised position, the spring 33 being fully extended with the head 34 abutting against and fully depressing the operating button of switching device 37. In this position, as may be seen in Figure 9, there is no closed circuit through the coil 58. As the handle 7 is moved about 47 degrees away from the "off" position in a clockwise direction, as viewed in Figure 4, the internal members assume the position shown in Figure 4 in which the roller 15 has passed the cam step 19 of member 16, with only a small movement of its operative end, and in which member 15 has just touched the cam step 21 of camming member 17. It will be seen that the operative end of the member 16 has been permitted to raise slightly under the bias of spring 28, with the screw head 29 slightly depressing the operating button 48 of switching member 36, this slight depression being insufficient, however, to effect a snap action of the device. It will further be seen that member 15 has not forced the operative end of member 17 downward against the bias of spring 33, the operating button of switching device 37 not having been permitted to move.

As the operating handle is moved only about six degrees further in the direction to cause clockwise movement of the roller 15 from the position shown in Figure 4, the roller rides up cam step 21 of camming member 17, forcing the operative end thereof downward, compressing spring 33 and permitting the operating button of switching device 37 to move outward under the influence of the internal spring of that device which corresponds to the spring 41 of device 36. A snap movement of the bridging contact member of device 37 is therefore effected, the bridging member leaving the D contacts shown in Figure 9 and electrically connecting the C contacts 66 and 68 together.

From an inspection of the diagrammatical circuit of Figure 9, it will be seen that current will now pass from supply line 54 through coil 58, conductor 61, to terminal 63, through the

movable contacts and bridging member 46 to terminal 62, through conductor 67 to terminal 68, through the movable contacts and bridging member of the device 37 to terminal 66, and thence to the supply line 56 via the conductor 64. The energization of coil 58 will cause the contacts 57 (and the contact 74) to close, thereby connecting the motor 53 to all three supply lines 54, 55 and 56. Under this condition the motor will run, and it should be noted that the motor may be "inched" by moving the operating handle only about six degrees, the motor running when the roller 15 has reached the left edge of the cam step 21, as viewed in Figure 4, the motor stopping when the operating handle is moved so as to cause the roller 15 to return to the right edge of step face 21, the position illustrated in Figure 4.

If normal running of the motor, as distinguished from "inching," is desired, the operating handle 7 may be moved from the position of Figure 4 in a direction which will cause the roller 15 to move in a clockwise direction to the position illustrated in Figure 5. As this motion progresses, the roller 15 will, first, cause the operation of switch 37 as previously described, electrically connecting the C terminals of Figure 9 together; second, as the roller 15 passes the cam face 18 of the camming lever 16, the spring 28 is permitted to further expand, forcing the screw head 29 to depress operating lever 48 of switching device 36 to such a degree that the device 36 is operated. The movable contacts 44 and 45 and the conducting bridging member 46 of device 36 are thereby moved from the position shown in Figure 8 into a position in which the movable contacts engage the stationary contacts 51 and 52. Referring to Figure 9, the terminals A are disconnected, and the terminals B are connected together. In this position of the device, the motor will continue to run, inasmuch as the holding contact 74 is closed, maintaining coil 58 energized.

It should be noted that in this position, should an overload occur which is sufficient to open circuit protective elements associated with the circuit, or should a condition of low voltage be experienced, the coil 58 will immediately become deenergized, causing the contacts 57 and 74 to open and the motor 53 to stop. After such an occurrence, the motor may not be restarted until the operating handle has been moved through an arc such that the roller 15 has passed cam step 21 of camming member 17 and both cam steps 18 and 19 of camming member 16, since it is not until step 19 is passed that the switch will be operated.

With the above operation, it will be seen that after opening of the motor controlling switch by deenergization of the coil 58 for any reason, that it is impossible for the motor to be reconnected to the line by a reenergization of the circuit until the handle 7 has been moved to its full "off" position. This presents an involuntary operation of the mechanism controlled by the motor after a failure has occurred and is particularly desirable in cases where such involuntary operation might effect damage if occurring in the middle of an operating cycle. With the device of this invention, after such failure, a voluntary act of an operator must be performed before a motor will be reenergized.

It will readily appear that the device of the present invention may be connected in a variety of positions and that the device therefore imparts a very large measure of flexibility to any

system with which it is associated. For example, operating conditions may require that the operating handle be on the left side, instead of on the right side as in the specific embodiment described. This requirement may be met by, first, inverting the device; then, by removing the connections to the device shown in Figure 9, and reconnecting conductor 67 between terminals 71 and 73, connecting conductor 64 to terminal 72, conductor 59 to terminal 71, and conductor 61 to terminal 69. The device will operate as described above with the "off" position again occurring when the operating handle is in its most raised position.

Similarly, the device may be easily converted to provide either left or right hand operation in which the "off" position occurs when the operating handle is in its most lowered position by merely reversing the position of the operating handle. It will be seen, therefore, that the device of the present invention is highly adaptable and may be readily adjusted to meet the requirements of all operating conditions.

While certain preferred embodiments of the invention have been specifically disclosed, it is understood that the invention is not limited thereto, as many variations will be readily apparent to those skilled in the art and the invention is to be given its broadest possible interpretation within the terms of the following claims:

What is claimed is:

1. In an electrical control station, a first switching mechanism, means for operating said first mechanism including a lever having one camming surface, a second switching mechanism, means for operating said second mechanism including a second lever having at least two spaced camming surfaces, means for mounting said levers in a contiguous relationship with said one camming surface between said two camming surfaces, operating means, and means for effecting movement of said operating means across all said camming surfaces.

2. In an electrical control station, a first lever having a single cam stop, a second lever having at least a pair of spaced cam steps, operating means, means for operatively relating said operating means to the cammed surfaces of said levers, means mounting said levers so that said operating means engages one of said pair of cam steps and said single cam step before engaging the other of said pair as said operating means is moved in one direction along the length of said levers, said operating means upon engaging said single cam step effecting a movement of said first lever substantially equal to the movement imparted to said second lever by the operation of said operating means upon both of said pair of cam steps, and a pair of switching mechanisms operated by said levers.

3. In an electrical control station, a first lever having a single cam step, a second lever having at least a pair of spaced cam steps, operating means, means for operatively relating said operating means to the cammed surfaces of said levers, means mounting said levers so that said operating means engages one of said pair of cam steps and said single cam step before engaging the other of said pair as said operating means is moved in one direction along the length of said levers, said operating means upon engaging said single cam step effecting a movement of said first lever substantially equal to twice the movement imparted to said second lever by the operation of said operating means upon either of said pair

of cam steps, and a pair of switching mechanisms operated by said levers.

4. In an electrical control station, a first lever having at least two spaced camming steps, a second lever having at least one cam step, biasing means for said levers, means pivotally mounting said levers, means including an operator operating upon both of said levers, means for moving said operator against the cammed steps of said levers to overcome said biasing means, the second of said levers being moved against its biasing means by the operation of said operator upon said one cam step a distance substantially equivalent to the distance the first of said levers is moved against its biasing means by the operation of said operator upon both of said cam steps, and a pair of switching mechanisms operated in response to the movement of said levers.

5. In an electrical control station, a first lever having at least two spaced camming steps, a second lever having at least one cam step, biasing means for said levers, means pivotally mounting said levers, means including an operator operating upon both of said levers, means for moving said operator against the cammed steps of said levers to overcome said biasing means, the second of said levers being moved against its biasing means by the operation of said operator upon said one cam step a distance substantially equivalent to the distance the first of said levers is moved against its biasing means by the operation of said operator upon both of said cam steps, and a pair of switching mechanisms operated in response to the movement of said levers, and means for effecting operation of said switching mechanisms at predetermined lever positions.

6. In an electrical control station, a first lever having an arcuate surface with one cam step, a second lever having an arcuate surface with at least a pair of spaced cam steps, biasing means for said levers, means rotatably mounting said levers in a contiguous relationship with said one cam step between said pair of cam steps, an operator, means including an operating handle for pressing said operator against selected portions of said arcuate surfaces, a pair of switching mechanisms operated by said levers, and means for effecting operation of said switching mechanisms at predetermined lever positions.

7. In an electrical control station, a pair of switches, rectilinear operating means effecting the switching operation, said switching operation occurring at one position of the rectilinear operating means as said means is moved inward and at a different position of said means as said means is moved outward, a first lever with one cam step for actuating one of said operating means, a second lever having at least a pair of cam steps for operating the other of said operating means, means rotatably mounting said levers in side-by-side relationship so that said one cam step is between said pair of cam steps, an operator, and means including an operating handle for selectively positioning said operator along said levers.

8. In an electrical control station, a pair of switches, rectilinear operating means effecting the switching operation, said switching operation occurring at one position of the rectilinear operating means as said means is moved inward and at a different position of said means as said means is moved outward, a first lever with one cam step for actuating one of said operating means, a second lever having at least a pair of cam steps for operating the other of said oper-

ating means, an operator, said operator upon engaging said single cam step effecting a movement of said first lever substantially equal to the movement imparted to said second lever by the operation of said operator upon both of said pair of cam steps, and means for moving said operator.

9. In an electrical control station, a pair of switches, rectilinear operating means effecting the switching operation, said switching operation occurring at one position of the rectilinear operating means as said means is moved inward and at a different position of said means as said means is moved outward, a first lever with one cam step for actuating one of said operating means, a second lever having at least a pair of cam steps for operating the other of said operating means, means rotatably mounting said levers in side-by-side relationship so that said one cam step is between said pair of cam steps, an operator, means including an operating handle for selectively positioning said operator along said levers, said operator upon engaging said single cam step effecting a movement of said first lever substantially equal to the movement imparted to said second lever by the operation of said operator upon both of said pair of cam steps.

10. In an electrical control station, a pair of switches, a first lever having a single cam step for operating one of said switches, a second lever having a pair of cam steps for operating the other of said switches, means rotatably mounting said levers, an operator, and means for pressing said operator against all said cam steps to effect rotation of said levers, said single cam step being approximately equal in height to the sum of the heights of said pair of cam steps.

11. In an electrical control station, a pair of switches, a first lever having a single cam step for operating one of said switches, a second lever having a pair of cam steps for operating the other of said switches, means rotatably mounting said levers, an operator, and means for pressing said operator against all said cam steps to effect rotation of said levers, said single cam step being approximately twice the height of either of said pair of cam steps.

12. In an electrical control station, a first lever having an arcuate surface with one cam step, a second lever having an arcuate surface with at least a pair of spaced cam steps, biasing means for said levers, means rotatably mounting said levers, circuit controlling mechanisms having actuators, means mounting said circuit controlling mechanisms near the free ends of said levers whereby said actuators are operated by movement of the free ends of said levers, and operating means including a member movable longitudinally along the surfaces of said levers having said cam steps, said member effecting rotation of said levers about said rotatable mounting against the operation of said biasing means to effect operation of said circuit controlling mechanisms.
